CONTACTS FOR ELECTRICAL DEVICES

Vernon Hellstern, St. Louis, Mo., assignor to James R. Kearney Corporation, St. Louis, Mo., a corporation of Missouri

Application May 31, 1951, Serial No. 229,055

3 Claims. (Cl. 339—64)

This invention relates generally to contacts for electrical devices, and more specifically to contacts for electrical cutouts of the housed type, the predominant object of the invention being to provide such a contact which is of simple and inexpensive construction and arrangement and which is capable of performing its intended function in an improved and highly efficient manner.

Fig. 1 is a fragmentary vertical sectional view of a housed electrical cutout having contacts constructed and arranged in accordance with this invention, and showing the fuse cartridge of the cutout in its closed-circuit position.

Fig. 2 is a fragmentary vertical sectional view similar to Fig. 1 but showing the fuse cartridge of the cutout in the open-circuit position.

Fig. 3 is a fragmentary horizontal sectional view taken on line 3—3 of Fig. 2.

Fig. 4 is a front elevational view illustrating the contacts of the cutout shown in Figs. 1 and 2.

In the drawings wherein is shown for purposes of illustration, merely, one embodiment of the invention, A designates an electrical cutout of the housed type having a housing 1 formed of porcelain, or other suitable electrical insulating material, said housing 1 being closed at its top, sides, and rear, and being open at front and at its bottom. At the open front of the housing 1 a door 2 is provided, said door being hinged to the housing at the lower portion of said door so that the upper portion of said door may swing outwardly and downwardly with respect to the housing. The door 2 is provided at its upper end with a spring latch element 3, said latch element having a portion 4 which is projected into a cavity 5 formed in the top wall of the housing 1 so as to latch the door in its closed position with respect to the housing 1.

For the purpose of illustrating the use of the present invention the door 2 has mounted thereon a fuse cartridge 6 which is supported for vertical movement by an extension 2' that is projected rearwardly from the door 2, a portion of the tube structure 7 of the fuse cartridge 6 being extended through an opening 8 formed through the extension 2'. The fuse cartridge 6 is provided with an upper portion 9 of increased diameter, an annular shoulder 10 being provided at the bottom of said upper portion 9 which serves as an abutment that engages the top face of the extension 2' and limits downward movement of the fuse cartridge when said fuse cartridge moves toward the open-circuit position (see Fig. 2). The fuse cartridge is provided with a cap 11 that screws on an upper portion of the tube structure of said fuse cartridge and clamps the upper portion of a fuse link 12 within the upper part of said tube structure. The fuse link passes downwardly through the tube structure of the fuse cartridge and at its lower end said fuse link is attached to mechanism (not shown) whereby said fuse link, when intact, serves to retain the fuse cartridge in the elevated position in which it is shown in Fig. 1. However, when the fuse

2

link is ruptured, because of the presence of an electrical fault in the circuit in which the cutout A is interposed, the fuse cartridge drops downwardly to the position in which it is shown in Fig. 2.

5 The cutout A is provided with an upper incoming contact structure 13 and a lower outgoing contact structure 14 which are engaged by portions of the fuse cartridge 6 so as to bridge the gap between said contact structures. The upper contact structure 13 comprises a strip of metal, or other material, which is characterized by being a good conductor of electricity. The strip is shaped as is shown to good advantage in Figs. 1 and 2 to provide a contact member 15; that is to say, said strip includes a vertically disposed portion 16 from the upper end of which a rearwardly extended, horizontal portion 17 is projected, a vertical portion 18 that extends upwardly from the rear end of said horizontal portion 17 and which merges into an upper, horizontal, forwardly extended portion 19, a portion 20 which extends downwardly from the forward end of said upper portion 19 and which merges into a forwardly extended portion 21. The portions 16 and 20 are secured together by a pair of rivets 22, and said portion 21 has formed therein an offset portion 23 and is provided at its forward end with an upwardly and forwardly inclined portion 24. The portion 20 of the contact 13 has formed therethrough a pair of screwthreaded openings in which are supported for screwthreaded adjustment clamping screws 25, which serves a purpose to be hereinafter set forth.

10 30 The rear wall of the housing 1 has formed therein an opening 26 in which is disposed a socket member 27, said socket member being provided with a screwthreaded opening 28 and having annular ribs 29 formed exteriorly thereof. The socket member is secured in place within the opening 26 by being embedded in a body 30 of lead, or other suitable material, which is disposed in said opening 26. The structure of the upper contact 13 includes a channel-shaped member 31 which serves as a base member and is disposed against the inner face of the rear wall portion of the housing in which the opening 26 is formed, the opposed side flanges of said channel-shaped member being projected forwardly, as is shown to good advantage in Fig. 3. The channel-shaped member has an opening 32 formed therethrough through which the shank portion of a bolt 33 is extended, the rear portion of said bolt shank being screwed into the screwthreaded opening 28 of the socket member 27. The bolt 33 is provided with a head portion 33' and embracing the shank portion of said bolt is a sleeve 34 which contacts at one of its ends with the inner face of the head portion of the bolt and at its opposite end with a forward face of the channel-shaped member 31. Arranged in embracing relation with respect to the sleeve 34 is a coil spring 35, said coil spring contacting at one end thereof with the forward face of the portion 16 of the contact member 15 and at its opposite end with the inner face of the head portion 33' of the bolt 33.

15 35 40 45 50 55 60 65 70

The lower contact structure 14 resembles the upper contact structure 13 in construction and arrangement in that it includes an externally ribbed socket member 36 which is leaded in an opening 37 formed in the rear wall of the housing 1. The socket member 36 is provided with a screwthreaded opening that receives a portion of the shank of a bolt 38, said bolt shank being extended through an opening 39 formed through a vertical portion 40 of a strip of material which produces the contact member 41 of the contact structure 14, and through an opening formed through a wall of a channel-shaped member 42 which serves as a base member. A portion of the shank of the bolt 38 is embraced by a sleeve 43 which contacts at one of its ends with a wall of the channel-shaped mem-

3
ber 42 and at its opposite end with the inner face of the head 38' of the bolt 38, said sleeve in turn being embraced by a coil spring 44 which contacts at one end thereof with the forward face of the vertical portion 40 of the contact member 41 and at its opposite end with the inner face of the head of the bolt 38.

The strip of material which produces the contact member 41 includes a horizontal portion 45 that extends rearwardly from the lower portion of the vertical portion 40, a vertical portion 46 which extends downwardly from the inner end of said horizontal portion 45, a horizontal portion 47 that extends forwardly from the lower end of said vertical portion 46, a vertical portion 48 which extends upwardly from the forward end of the horizontal portion 47, and a portion 49 that extends forwardly from the upper portion of the vertical portion 48. The portions 40 and 48 are secured together by means of a pair of rivets 50, and the extreme upwardly curved, forward end of the portion 49 of the contact member 41 is provided with a recess 51. Also, the vertical portion 48 has a pair of screwthreaded openings 52 formed therethrough which screwthreadedly receives clamping screws 53 that serves a purpose to be hereinafter set forth.

As has been previously stated herein, the fuse link 12 serves, when intact, to maintain the fuse cartridge 6 in an elevated position with respect to the door 2 and when said door is closed and the fuse cartridge is in such elevated position the cap 11 of the fuse cartridge contacts with the contact member of the upper contact structure 13, while the shoulder 6' of said fuse cartridge contacts with the contact member of the lower contact structure 14, as is shown in Fig. 1. It is important to note that when the fuse cartridge is in its circuit-closing position, as is shown in Fig. 1, the upper contact member 15 and the lower contact member 41 are canted slightly in an upward direction, the coil springs 35 and 44 of the upper and lower contact structures permitting such canting of said contact members. As a result of the canting of the contact members of the upper and lower contact structures very intimate contact is obtained between the contact members and the portions of the fuse cartridge with which said contact members contact because of the force exerted by the coil springs 35 and 44. Also, because the incoming and outgoing electrical conductors Ca and Cb are clamped directly to the contact members of the upper and lower contact structures 13 and 14 by the clamping screws 25 and 53, the electrical connection between said electrical conductors and the fuse cartridge is about as perfect as it is possible to make, as the only places where transfer of current between contacting parts takes place is where the contact member of the upper contact structure 13 contacts with the cap 11 of the fuse cartridge, and where the contact member of the lower contact structure 14 contacts with the shoulder 6' of the fuse cartridge, and the contact engagements at these points are made very intimate because of the forces exerted by the coil springs 35 and 44.

When, in the use of the illustrated switch disclosed herein the fuse link 12 is ruptured, the fuse cartridge 6 drops downwardly, thereby separating the cap 11 and the shoulder 6' of the fuse link from the contact members of the upper and lower contact structures 13 and 14 and interrupting the circuit in which the switch is interposed. It is to be noted that the coil springs 35 and 44 of the upper and lower contact structures 13 and 14 facilitate such downward movement of the fuse cartridge 6, because said coil springs exert downwardly directed forces against parts of said fuse cartridge. When the fuse link is in use in the switch has been ruptured, as described above, the door 2 is opened and removed from the housing, after which a new fuse link is introduced in place in the fuse cartridge so that it retains the fuse cartridge in its elevated position with respect to the door. The door 2 is then replaced in association with the housing 1 and is closed in on the housing, the cap 11 and the shoulder 6'

of the fuse cartridge riding under the contact members of the upper and lower contact structures 13 and 14 and moving their outer end portions upwardly slightly, and the latch element 3 eventually latches the door 2 in its closed position.

5 I claim:

1. A contact structure for an electrical device comprising a contact member, means for movably supporting said contact member, said supporting means comprising a screwthreaded element having an abutment, a socket member for screwthreadedly receiving a portion of said screwthreaded element, a base member having an opening through which said screwthreaded element extends, a separate sleeve embracing a portion of said screwthreaded element, said sleeve contacting at one end thereof with said abutment of said screwthreaded element and at its opposite end with said base member, a coil spring embracing said sleeve and contacting at one of its ends with said abutment of said screwthreaded element and at its opposite end with a portion of said contact member to which said coil spring applies pressure, and means for connecting an electrical conductor directly to said contact member.

10 2. A contact structure for an electrical device comprising a contact member formed from a single length of material shaped to provide a substantially vertical portion and a substantially horizontal portion, means for movably supporting said contact member, said supporting means comprising a screwthreaded element having an abutment, a socket member for screwthreadedly receiving a portion of said screwthreaded element, a channel-shaped base member having an opening through which said screwthreaded element extends, a separate sleeve embracing a portion of said screwthreaded element, said sleeve contacting at one end thereof with said abutment of said screwthreaded element and at its opposite end with said base member, a coil spring embracing said sleeve and contacting at one of its ends with said abutment of said screwthreaded element and at its opposite end with a portion of said contact member to which said coil spring applies pressure, and means for connecting an electrical conductor directly to said contact member.

15 3. A contact structure for an electrical device comprising a contact member formed from a single length of material shaped to provide a substantially vertical portion and a substantially horizontal portion, means for movably supporting said contact member, said supporting means comprising a screwthreaded element which is extended through an opening formed through a portion of said contact member and having an abutment, a socket member for screwthreadedly receiving a portion of said screwthreaded element, a channel-shaped base member having an opening through which said screwthreaded element extends, a separate sleeve embracing a portion of said screwthreaded element, said sleeve contacting at one end thereof with said abutment of said screwthreaded element and at its opposite end with said base member, a coil spring embracing said sleeve and contacting at one of its ends with said abutment of said screwthreaded element and at its opposite end with a portion of said contact member to which said coil spring applies pressure, and means for connecting an electrical conductor directly to said contact member.
